UNITED STATES PATENT OFFICE

LINDSLEY SCHEPMOES, OF NEW HAVEN, CONNECTICUT, ASSIGNOR TO THE SAFETY CAR HEATING & LIGHTING COMPANY, A CORPORATION OF NEW JERSEY

LIGHTING FIXTURE

Application filed February 19, 1929. Serial No. 341,129.

This invention relates to lighting fixtures and more particularly to ceiling fixtures for the interior of railway vehicles and the like.

One of the objects thereof is to provide a practical ceiling fixture which will be of simple structure and effective and artistic appearance. Another object is to provide a fixture of the character described which may be easily assembled, conveniently cleaned inside and out, and which to a high degree will be free from the annoying rattling and breakage to which such fixtures are liable. Another object is to provide a ceiling fixture practically designed and constructed to reveal and illuminate certain non-luminous ornamental parts thereof. Other objects will be in part obvious and in part pointed out hereinafter.

The invention accordingly consists in the features of construction, combinations of elements and arrangements of parts which will be exemplified in the structure to be hereinafter described and the scope of the application of which will be indicated in the following claims.

In the accompanying drawings, in which is shown one of various possible embodiments of my invention,

Figure 1 is a bottom plan view of a ceiling fixture showing a part of the bowl broken away;

Fig. 2 is a cross-sectional view taken on the line 2—2 of Fig. 1;

Fig. 3 is in part a top plan view and in part a sectional view taken on the line 3—3 of Fig. 2;

Fig. 4 is a detailed cross-section taken on the line 4—4 of Fig. 3; and

Fig. 5 is a detailed cross-section taken on the line 5—5 of Fig. 3.

Similar reference characters refer to similar parts throughout the several views of the drawings.

Referring in detail to the drawings, there is shown at 1 a ceiling plate or ring comprising a downwardly and inwardly concave annular body portion 2 adapted for reception within a circular opening in the car ceiling 3. Flange 4 extending outwardly from the lower edge of body portion 2 underfits the edge of

the ceiling opening to which it is secured by means of bolts 5. At its inner periphery, the ring 1 flares upwardly as at 6, and at its top edge terminates in an internal flange 7 against which the bezel 8 is designed to rest when in closed position. A flange 9 on the bezel 8 supports the flange 10 of a glass bowl 11, a piece of felt packing 12 being interposed between the said flanges to protect the bowl from shock and to prevent rattling. Clips 13, fastened to the upper edge of the bezel by means of screws 13', overlap the edge of the bowl and hold it in place. At 45 is shown a piece of ornamental appliqué which covers a portion of the downwardly concave surface of the ceiling ring and is riveted thereto as at 46.

The reflector 14 is supported above the bowl by means of upwardly and inwardly turned lugs 15 which form a part of the ceiling ring and to which the reflector is fastened with screws 16. A socket support 17 is fastened by means of screws 18 to the upper side of reflector 14 and extends over in spaced relation to an opening 19 in the center of said reflector. A lamp socket 20

attached to said support depends downwardly through the opening 19 in a convenient position for the reception of the incandescent lamp 21. The upwardly turned flange 6 of the ceiling ring is cut away at a suitable point in its circumference to permit of the passage of the hinge member 23 which is fastened by means of screws 24 to an embossed section 25 of the ceiling ring. This hinge member has at its inner end perforated lugs 26 which register with other perforated lugs 27 provided upon the edge of the bezel. A pin 28 completes the hinge. Diametrically opposed to the hinge, as shown in Figs. 1, 2 and 3 of the drawings, provision is made for a catch member 29, which is supported by a pin 30 between the projecting ribs 31 and 32 of a bracket 33 having flanges 34 and 35 through which pass screws 36 and 37 to attach said bracket to a plane surface 38 of the ceiling ring. This catch is normally held by means of a spring 39 under a part of the bezel 9 to hold the latter in closed position. A light-shield 40 is screwed to the upper rim of the bezel above the hinge, over-

lying the edge of the bowl in a manner similar to the clips 13. This plate serves to shield the hinge section from the bright interior of the fixture so as to prevent streaks of light showing through the structure about the hinge.

The ceiling bolts 5 have ornamental heads, and pieces of ornamental appliqué are disposed at other points to the inner side of the ceiling ring, as shown at 42 in Fig. 1, in symmetrical arrangement with respect to the bolts 5, and adding generally to the attractive appearance of the construction as a whole.

One of the dominant features of the invention resides in that feature of this construction making it possible to install the fixture in a recess in the ceiling, thus eliminating the glare of light rays reflected from the ceiling of the vehicle, and removing from the line of vision of the occupants of the vehicle the details of construction of the globe-supporting mechanism. At the same time this construction makes it possible artistically to embellish certain parts of the ceiling ring, which will be brightly illuminated and stand out in attractive relief against the less brightly lighted ceiling. As ordinarily constructed, such ceiling fixtures have a flat or projecting ceiling ring supporting the luminous bowl. With such an arrangement, the fixture shows up as a brightly illuminated glass surface surrounded by a dimly illuminated band or area of metal. In such a structure, ornamental effects produced in the design of the metal parts are wasted, as they are not apparent to the beholder. On the other hand, with applicant's construction, the ornamental parts of the ceiling ring are brightly illuminated, and its design is clearly visible, adding greatly to the pleasing effect of the fixture, and consequently of the illuminated vehicle in which it is installed.

It is to be noted also that this construction takes little from the head-room within the vehicle itself, so that lower ceilings may be employed,—a feature of considerable importance in the design and construction of a certain type of vehicle, as, for example, a motor bus or cab. The rigid construction of the hinge member and the spring-pressed catch hold the bezel firmly in closed position and prevent rattling and jarring, while, at the same time, this construction affords ready accessibility to the interior and makes it a simple matter to keep the reflector and interior of the bowl clean and efficient. The ring or section of appliqué ornamentation 45 is fitted into place before assembly, when the rivet members 46 may easily be headed over and protected by soldering. The ornamental ring-retaining bolts 5 and alternately disposed false bolt-heads 42 are also se-

cured to the ring by soldering, and thus form an integral part of the ring.

As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In lighting fixtures, in combination, a ceiling ring adapted to fit a ceiling opening and having a visibly exposed surface disposed above the ceiling surface, and a luminous bowl supported by said ring to illumine the exposed surface thereof.

2. In lighting fixtures, in combination, a ceiling ring adapted to fit a ceiling opening and having a visibly exposed surface disposed above the ceiling surface, a luminous bowl supported by said ring to illumine the exposed surface thereof, and means imparting an ornamental appearance to said exposed surface.

3. In lighting fixtures, in combination, a supporting ring adapted to fit an opening in a supporting surface and having a recessed surface extending inwardly of said supporting surface, and a bowl held by said ring and adapted to throw light upon said recessed surface.

4. In lighting fixtures, in combination, a supporting ring adapted to fit an opening in a supporting surface and having a recessed surface extending inwardly of said supporting surface, a bowl held by said ring and adapted to throw light upon said recessed surface, and ornamental appliqué covering portions of said surface.

5. In lighting fixtures, in combination, a ceiling ring adapted to fit into a ceiling recess and comprising a flange adapted to underlie the edges of said ceiling recess and an upwardly and inwardly extending body portion disposed inwardly of said recess, means for attaching said flange to the ceiling, and a bowl supported within said ring to throw light upon the upwardly extending body thereof.

6. In lighting fixtures, in combination, a ceiling ring adapted to fit a ceiling opening, a light-diffusing bowl, and means for supporting said bowl adapted itself to be supported above said opening by said ceiling ring, said ring being recessed to present a visible surface extending inwardly above the edge of said opening.

7. In lighting fixtures, in combination, a ceiling ring adapted to fit a ceiling opening, a light-diffusing bowl, and means upon said ring above said opening for supporting said bowl, said ring having a visible surface disposed above said opening adapted to receive illumination from said bowl.

8. In lighting fixtures, in combination, a ceiling ring adapted to fit a ceiling opening, a light-diffusing bowl, means hinged upon said ring above said opening for supporting said bowl, and releasable means for holding said bowl-supporting means in closed position.
9. In lighting fixtures, in combination, a ceiling ring adapted to fit a ceiling opening, a light-diffusing bowl, means hinged upon said ring above said opening for supporting said bowl, and a spring catch for releasably holding said bowl-supporting means in closed position.
10. In lighting fixtures, in combination, a ceiling ring comprising a circumferential flange, a downwardly and inwardly concave body portion extending above said flange, and upwardly and inwardly extending supports positioned above said body portion, a reflector carried by said supports, bowl-supporting means positioned within said ring above said flange, and a bowl supported by said supporting means and spaced inwardly from said ring.
11. In lighting fixtures, in combination, a ceiling ring comprising a circumferential flange, a downwardly and inwardly concave body portion extending above said flange, and upwardly and inwardly extending supports positioned above said body portion, a reflector carried by said supports, bowl-supporting means positioned within said ring above said flange, a bowl supported by said supporting means and spaced inwardly from said ring, and means for releasably securing said bowl-supporting means to said ring.
12. The combination with a recessed vehicle ceiling, of means comprising a reflector and a lamp socket support positioned above said recess, means disposed beneath said reflector and above said recess for supporting a bowl, a ceiling ring adapted to be fastened to the ceiling and extend upwardly within said recess to provide support for both said means, and a bowl positioned within said ring in a position to throw light upon the surrounding surface thereof.
13. In lighting fixtures, in combination, a ceiling ring comprising a laterally extending flange adapted to engage a supporting surface and an upwardly offset portion presenting a recessed visible surface disposed inwardly of said supporting surface, and a bowl supported upon said offset portion and adapted to throw light upon said recessed surface.
14. In lighting fixtures, in combination, a ceiling ring comprising a laterally extending flange adapted to engage a supporting surface and an upwardly offset portion presenting a recessed visible surface disposed above said supporting surface, a bowl supported upon said offset portion and adapted to throw light upon said recessed surface, and a re-
- flector supported by said ring above said bowl.
15. In lighting fixtures, in combination, a ceiling ring adapted to fit a ceiling opening, a light-diffusing bowl, means upon said ring above said opening for supporting said bowl, said ring having a visible surface disposed above said opening adapted to receive illumination from said bowl, and means imparting an ornamental appearance to said exposed surface.
- In testimony whereof, I have signed my name to this specification this 2d day of February, 1929.
- LINDSLEY SCHEPMOES.
